2,567,116

MAGNETIC FREQUENCY CHANGER HAVING
PARTIAL GAPSHarold J. McCreary, Lombard, Ill., assignor to
Automatic Electric Laboratories, Inc., Chicago,
Ill., a corporation of Delaware

Application May 19, 1950, Serial No. 163,043

4 Claims. (Cl. 321—68)

1

This invention relates in general to frequency changers which utilize saturated ferromagnetic cores to produce an alternating current having a frequency which is a harmonic or sub-harmonic of the frequency of an alternating current source; and in particular to improvements in the construction of the magnetic core and the arrangement of electrical circuits of such frequency changers.

An object of the present invention is to provide a frequency changer utilizing a magnetic cross valve in which a partial gap is inserted to create odd harmonics.

Other objects and features will appear upon a further perusal of the specification taken in conjunction with the accompanying drawing which illustrates several embodiments of the invention in the form of schematic circuit diagrams.

Fig. 1 is a diagrammatic representation of the frequency changer having intersecting partial gaps in the center of the magnetic cross valve core.

Fig. 2 is a diagrammatic representation of a frequency changer having partial gaps extending diagonally from two intersecting members of the magnetic cross valve core.

In the present invention two coils are wound through opposite diagonal corners of the magnetic cross valve so that there is no mutual inductance between the respective coils. However, when the magnetic core reaches a degree of saturation a differential flux is set up to induce a voltage in one of the coils. A partial gap is used in the magnetic cross valve core to emphasize the odd harmonic rather than the even harmonic which would be caused by D. C. saturation.

Referring now to Fig. 1 which shows a magnetic cross valve 1. The magnetic cross valve 1 herein used may be of the type disclosed in Patent No. 2,445,857, issued on July 27, 1948, to the present inventor and also in Patent No. 2,461,992, issued on February 15, 1949, to the present inventor. Primary winding 2 is shown diagonally wound through a pair of opposite corners of the intersecting members of the magnetic cross valve 1. Secondary winding 3 is wound through another pair of diagonal corners of the intersecting members of the magnetic cross valve 1 and is displaced by 90 degrees from the primary winding. The result, therefore, is that there is no mutual inductance between the respective coils until the magnetic core has reached a degree of saturation. A condenser 4 is included in the secondary circuit to tune the secondary circuit to the desired output frequency.

5 A partial gap 9 is shown at the center of the magnetic cross valve core 1 and is positioned in a plane parallel to that of the primary winding and extends in a direction from one corner to the opposite diagonal corner. Another partial gap 10 is shown at the center of the magnetic cross valve core 1 and is perpendicular to the partial gap 9. The partial gap 10 extends between the other pair of diagonal corners from which partial gap 9 is extended. The function of the partial gap is to emphasize the odd harmonics. In magnetic circuits the gap will have a different flux density than the metallic core structure. Therefore, at 10 a degree of saturation, a differential flux is set up at the center of the magnetic cross valve to induce a voltage in the secondary winding.

An input alternating current voltage is fed to the primary winding 2. The current flow in the primary winding produces an alternating flux in 15 the core 1. A voltage is induced in the secondary winding 3 in a manner previously described. The output signal of the secondary winding is an odd harmonic.

Referring now to Fig. 2 which shows a magnetic cross valve 5. The magnetic cross valve 5 herein used may be of the type disclosed in Patent No. 2,461,992, issued on February 15, 1949, to the present inventor and also in Patent No. 2,445,857, issued on July 27, 1948, to the present inventor.

20 A primary winding 6 is wound through a pair of opposite diagonal corners of the magnetic cross valve 5. A secondary winding 7 is wound through the opposite pair of diagonal corners of the magnetic cross valve 5 and is displaced 90 degrees from the primary winding. A condenser 12 is included in the secondary circuit to tune the secondary circuit to the desired output frequency.

25 A partial air gap 8 is shown extending in a diagonal direction from the lower left-hand corner of the intersection to a point of close proximity to the center of the magnetic cross valve 5. Another partial gap 11 is shown extending downward from the upper right-hand corner of the intersection and is extended in close proximity to the center of the magnetic cross valve core 5. The partial gaps shown in Fig. 2 are effective on only one winding in much the same way as superimposed D. C. flux would be effective on only one winding. It is therefore possible to produce 30 20 cycles from a 60 cycle input or it is possible to produce 180 cycles from a 60 cycle input. The desired output frequency is produced by changing the size of the condenser 12 so as to tune the secondary circuit to the desired odd harmonic.

35 The partial gaps in Fig. 2 also emphasize the odd

2

harmonics, when a degree of saturation is reached in the magnetic core 5. The partial gaps will produce a flux differential to induce a voltage in the secondary winding 7, since the flux density of the air gap is different from the flux density of the ferromagnetic substance used to form the core of a magnetic cross valve 5. The operation is similar to that described in reference to Fig. 1.

Although I have described my invention with a certain degree of particularity, it should be understood that the present disclosure has been made only by way of example and that numerous changes in the details of construction and arrangement of parts may be resorted to without departing from the spirit and scope of the invention as hereinafter claimed.

What is claimed is:

1. In a frequency changer, a magnetic core structure having two intersecting members, a primary winding wound through opposite diagonal corners of the intersection, a source of current for energizing said primary winding to provide the input signal, a secondary circuit tuned to the desired output signal and wound through the other opposite corners of said intersection, and said magnetic core having partial gaps at the general area of core saturation to provide a flux differential in said core whereby an alternating current is induced in said secondary circuit having a frequency which is integrally related to the frequency of said source.

2. In a frequency changer, a magnetic core structure having two intersecting members, a primary winding wound through a pair of opposite diagonal corners of the intersection, a source of current connected to said primary winding for providing an input signal, a secondary circuit tuned to a desired odd harmonic and wound through the other pair of opposite corners of said intersection, and said magnetic core having partial gaps intersecting at the center of said magnetic core to provide a flux differential in said core whereby an alternating current is induced in said secondary circuit having a frequency which is an odd harmonic of the frequency of said source.

3. In a frequency changer, a magnetic core structure having two intersecting members to form opposite diagonal corners, a primary winding wound through a pair of opposite diagonal corners of the intersection, a source of current connected to said primary winding for providing an input signal, a secondary winding tuned to a desired harmonic and wound around said magnetic core so as to be at right angles to said primary winding, an output circuit connected to said secondary winding, and said magnetic core having partial gaps extending from a pair of opposite diagonal corners to provide a flux differential in said magnetic core whereby an alternating current is induced in said secondary winding having a frequency which is integrally related to the frequency of said source to be delivered to said output circuit.
4. In a frequency changer, a magnetic core structure having intersecting members, a primary winding wound through opposite diagonal corners of the intersection, a source of current for energizing said primary winding to provide the input signal, a secondary circuit tuned to the desired output signal and wound through the other opposite corners of said intersection, said magnetic cores having partial gaps angularly disposed with respect to said intersecting members at the intersection of the core members to provide a flux differential in said core whereby an alternating current is induced in said secondary circuit having a frequency which is integrally related to the frequency of said source.
